DITCH EXCAVATING BUCKET

Filed Nov. 12, 1925

FIG. 1.

FIG. 2.

FIG. 3.

FIG. 4.

INVENTOR
CHARLES HARRISON.

BY
Albert E. Schuch
ATTORNEY

UNITED STATES PATENT OFFICE.

CHARLES HARRISON, OF VANCOUVER, BRITISH COLUMBIA, CANADA.

DITCH-EXCAVATING BUCKET.

Application filed November 12, 1925. Serial No. 68,671.

To all whom it may concern:

Be it known that I, CHARLES HARRISON, a citizen of the Dominion of Canada, residing at Vancouver, in the Province of British Columbia, Canada, have invented certain new and useful Improvements in Ditch-Excavating Buckets, of which the following is a specification.

This invention relates to an improvement applicable to the bucket of a ditch excavator and designed to enable a ditch to be cut of a width in excess of that of the bucket and in a manner that the earth removed from this extra width is either delivered into the bucket as removed if the bucket is not full, or if the bucket will not receive it, it falls into the ditch to be removed on the next lift.

In a ditch excavator of this class the width of the ditch cut is practically that of the excavator bucket and if a wider ditch is required, a wider bucket must be used.

This requirement is objectionable not only on account of the expense of providing a separate bucket for every width of ditch to be cut and the inconvenience of having to remove one bucket and attach another, but is also open to objection in that where the ground being excavated is unusually hard or tough, as in hard-pan or clay, a narrow bucket is much more effective than a wide one, as the cutting edge of a wide bucket will not penetrate a hard earth to a sufficient extent to fill the bucket.

To overcome these difficulties I provide each side of the bucket with a supplementary plough-shaped scoop. These scoops are removably secured to the sides of the bucket and remove the earth from the sides of the ditch as cut by the bucket proper. The form of these scoops is such as to deliver the removed earth directly into the bucket if the same is not full, or if full the loosened earth falls into the ditch to be removed in the next lift.

The invention is fully described in the following specification, reference being made to the drawings by which it is accompanied, in which:—

Fig. 1 is an elevation of the scoop, which is the particular subject of this application, from the inside of the bucket.

Fig. 2 is a front view of the same.

Fig. 3, a sectional plan on the line 3—3 in Fig. 2, and

Fig. 4 is a perspective view of an excavating bucket showing the application of the side scoops thereto.

In these drawings 2 represents the bottom and 3 the sides of the bucket, 4 being the excavating teeth which are secured to the front edge of the bottom 2 to project outward from it.

The improvement consists in the provision of outwardly projecting side scoops 5 which are removably secured at 6 to the front edges of the sides 3 of the bucket adjacent the bottom 2. The cutting edges 7 of these scoops 5 are projected laterally outward from the sides and forward from the front edge thereof to an extent sufficient to provide a sloping delivery backward into the bucket, so that as the teeth 4 of the bucket excavate the bottom of the ditch, these lateral scoops will remove the earth from the sides and will deliver it into the bucket, and similarly as the bucket having scraped the bottom of the ditch, is drawn upward to the top, the scoops 5 will remove the earth from the sides of the ditch. If the bucket is full the earth removed by the scoops 5 will simply fall to the bottom of the ditch to be filled into the bucket during the next lift.

From the form of the scoops and their limited size and the fact that the earth is removed from the open sides of the ditch, the extra effort imposed on the excavating mechanism by these scoops is comparatively trifling, so that we are enabled to cut a greater width of ditch with a less size of excavator bucket. By drawing the excavator bucket up one side of the ditch or the other, a greater width of ditch can be excavated than the width over the scoops.

I am aware that side scrapers have heretofore been applied to the sides of ditch excavating buckets in order to enlarge the width of the ditch to provide clearance for the bucket, but such side scrapers do not deliver into the bucket, and their cutting edges are in planes parallel to the sides of the bucket: As a consequence where even moderately sized stones are encountered imbedded in the sides of the ditch they are

sufficient to resist the action of the side bucket and having a cutting edge which projects laterally outward and forward from the front edge of the sides of the bucket. 25
scrapers, whereas in the side scoops, which are the particular subject of this application, the cutting edges 7 are not in uniform
the cutting edges 7 are not in uniform
5 planes and are not parallel to the sides of the bucket, so that unless the stones are of abnormal size the scoops will readily remove them with the earth.

As the scoops are removably connected to
10 the sides of the excavator bucket, a selection of scoops of different projecting dimensions may be furnished to cut ditches of different widths, as it is considerably cheaper to have a selection of these relatively inexpensive
15 scoops than a selection of buckets of different widths as is the practice at present.

Having now particularly described my invention, I hereby declare that what I claim as new and desire to be protected in by Letters Patent, is:

20 1. The combination with a ditch excavating bucket, of a supplementary ear-like scoop removably secured to each side of the

2. The combination with a ditch excavating bucket, of a supplementary scoop removably secured to each side of the bucket, the cutting edge of which scoop angles laterally outward from the side and forward from the front edge of the same to deliver the material removed from the side of the ditch into the bucket. 30

3. A supplementary scoop for ditch excavating buckets having side walls, said scoop comprising a bifurcated body to fit over the edge of the bucket wall and a plate extending laterally from the body in front of and toward the outside of the bucket, 40 said plate having a continuous cutting edge and being curved and inclined so as to direct the material cut by it into the bucket.

In testimony whereof I affix my signature.

CHARLES HARRISON.
